UNITED STATES PATENT OFFICE.

SCHAMU M. MOSCHCOWITZ, OF NEW YORK, N. Y.

HEEL FOR BOOTS OR SHOES.

SPECIFICATION forming part of Letters Patent No. 288,842, dated November 20, 1883.

Application filed September 22, 1883. (Model.)

To all whom it may concern:

Be it known that I, SCHAMU M. MOSCHCOWITZ, a citizen of the United States, residing at New York, in the county and State of New York, have invented new and useful Improvements in Heels for Boots and Shoes, of which the following is a specification.

This invention has for its object to provide a novel heel for boots and shoes, more especially designed for ladies' boots; and the invention consists in the heel hereinafter described, and claimed, and illustrated in the accompanying drawings, in which—

Figure 1 represents a sheet of celluloid before its application to the heel. Fig. 2 represents a shoe-heel with the prepared sheet applied thereto. Fig. 3 represents another method of applying the sheet.

I will now describe my invention as applied to a shoe-heel.

Heretofore shoe-heels have been made of leather, or some composition of matter, or of wood covered with leather, or with an enamel applied in several distinct coats, and terminating at the upper edge of the heel. Heels made as described possessed demerits as well as merits, and my invention seeks to retain all the merits without the demerits, and with certain merits added. Celluloid is particularly adapted to the coating of the heels of boots and shoes, because it presents a surface closely imitating polished leather—tough, tenacious, and durable—and can by application, as I shall hereinafter describe, be made to readily take the mold of the heel without presenting any inequalities or sharp edges to break and lead to the subsequent peeling off of the coating. It also admits of variegated colors being given to the heel.

In the accompanying drawings, the letter A indicates a shoe-heel made of wood, of the form usually made for ladies' shoes; but it may be of any form, adapted to any kind of a shoe, whether for ladies', men's, or children's wear; and the letter B indicates the shell of celluloid forming the coating or covering for the heel. The celluloid is prepared in any of the well-known ways, and is either of a solid or of variegated colors, and is cut

into a form adapted to cover the exterior or exposed portion of the heel, and to lap over the edges thereof, so that the edges will be covered and present rather a rounding than a sharp edge. In order that the sheet of celluloid may better take the shape of the heel at its edges, especially along its upper and inner edges, the edges are slit, so that the sheet along the slitted portion may stretch, and thereby make a closer and neater connection with the heel at such parts, and also presenting a series of disconnected attaching-flaps, so that if by any possibility, for any reason, a portion of the edge should become loosened and pulled from close connection with the heel, the remaining portion will not be affected thereby, as it will be disconnected from the loosened portion. The sheet of celluloid can be applied to the heel in any of the well-known ways of applying or cementing the same to the other parts, either by a mold of suitable configuration and constructed with the well-known requisites for the application, or otherwise.

When the heel is covered as described, it is connected with the shoe in the ordinary way, and presents a beautifully-polished surface, very durable in use, and a heel light in weight and cheap of production, and, if desired, of variegated colors.

If desired, the heel may be first connected to the shoe and the sheet of celluloid then applied, so as to not only cover the exposed parts of the heel, but be extended up onto the upper portions of the shoe above the heel, so as to cover the seam or line of connection between the upper and heel, as illustrated in Fig. 3 of the drawings. When the coating is so applied, it gives a very pretty appearance to the shoe, and adds to the security of the connection between heel and upper, and also strengthens the upper. In attaching the celluloid to the upper, care must be taken not to employ a heel that will injuriously affect the material of which the upper is composed.

Having thus described my invention, what I claim is—

1. As an improved article of manufacture, the heel herein described and shown, con-

sisting of the body A and the shell B, composed of a sheet of celluloid, said shell being applied substantially as set forth.

2. A boot or shoe heel having a covering 5 of celluloid secured thereto, and extended to cover the seam or point of juncture between the heel and the upper, substantially as described.

In testimony whereof I have hereunto set my hand in the presence of two subscribing witnesses.

SCHAMU M. MOSCHCOWITZ.
